(57) **CLAIM**

The ornamental design for a mobile toilet vehicle, as shown and described.

DESCRIPTION

FIG. 1 is a perspective view of a mobile toilet vehicle of our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The evenly-spaced broken lines shown represent portions of the mobile toilet vehicle and form no part of the claimed design.

The three different tones of grayscale shading represent a contrast in appearance only between their regions and do not represent any particular color.

The dash-dot lines represent the boundary of the claimed design and form no part of the claimed design.
